WINDOW CONSTRUCTION

Paul Judson, Alhambra, Calif.

Application June 22, 1953, Serial No. 363,291

2 Claims. (Cl. 20—40)

This invention relates to window construction and, more particularly, to ventilating windows.

An object of the invention is to provide a ventilating window having a novel frame that is angular in vertical cross-section and is provided with movable sashes in the upper and lower portions of said frame, whereby the window is provided with transverse sashes that are angularly disposed with relation to the horizontal and the angle thereof variable, as desired, in the vertical plane of cross-section of the window.

Another object of the invention is to provide a window that has its sashes disposed at an angle to the horizontal when closed and, thereby, reducing glare and reflection of light passing therethrough.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes, embodiments of the present invention, which are given by way of illustration or example only.

In the drawing, like reference characters designate similar parts in the several views.

Fig. 1 is an elevational view, as seen from the outside, of a window construction according to the invention.

Fig. 2 is an enlarged vertical cross-sectional view as taken on line 2—2 of Fig. 1.

Fig. 3 is a fragmentary horizontal sectional view as taken on line 3—3 of Fig. 2.

Fig. 4 is a fragmentary cross-sectional view of a modification.

Fig. 5 is a fragmentary cross-sectional view of another modification.

Fig. 6 is a fragmentary cross-sectional view of another form of sash.

The window construction that is illustrated comprises, generally, a frame 10, and respectively upper and lower sashes 11 and 12 mounted in said frame. The frame is set in a rectangular opening 13 provided in a wall 14.

The frame 10 comprises two similar sides 15 and, as shown in Figs. 1 to 4, said sides are connected by a transverse member 16. The sides 15 are of triangular form and preferably of symmetrical or isosceles form. As best seen in Fig. 2, each triangular side has its base 17 disposed vertically in opening 13 and its two equal sides 18 extending outwardly from said opening and joining at apex 19. While the included angle between the sides may vary, an obtuse angle in the nature of 150 degrees is preferred. Thus, the protrusion of the sides from the wall is small with relation to the vertical dimension of the frame sides. The transverse member 16 spans between said frame sides at the apices 19 thereof and, to complete the frame 10, upper and lower transverse members 20 and 21, respectively, connect the other angles of said frame.

In the above manner, frame 10 is provided with an upper opening 22 and a lower opening 23, the former

2

sloping downward and outward and the latter downward and inward.

If desired, the two side frames may each be provided with a side window sash 24 which may be fixed or, as shown in Fig. 3, may be hinged at 25 to swing outward and increase the ventilation afforded by the construction.

The upper and lower sashes 11 and 12 are movably mounted in frame openings 22 and 23, respectively. The sashes may be moved in the same way or differently. For instance, each sash may be hinged to swing inward either on an upper or a lower hinge 26, as shown in the upper portion of Fig. 2; pivot on horizontal trunnions 27 so as to swing partly inward and partly outward, as in the lower portion of Fig. 3; or both pivot and slide, as shown in Fig. 4. In the latter case, the trunnions 27 mount slide-ways 28 and the sash 29 is slidingly movable in said slide-ways, as indicated by the dot-dash lines of Fig. 4.

Each sash is provided with a transparent pane 30 enclosed in a sash frame 31. While not shown, it will be understood that suitable latches, keepers, or the like, may be used to retain the closed and open positions of said sashes.

In order to eliminate the obstruction of transverse member 16 and, thereby, provide an unobstructed space between the upper and lower sashes, when open, said member 16 may be omitted, as shown in Fig. 5, wherein said upper and lower sashes close against each other, as at 32. In other respects, the construction may follow the forms of Figs. 2 and 4.

Instead of the panes 30, the sashes may be provided with sets of overlapping transparent louvres 33, as shown in Fig. 6. When open, as shown by the dot-dash lines, said louvres provide spaces which, together with the frame openings formed when the sashes are moved to open position, create ventilating areas that are quite large relative to the size of the window. One or both sashes of the window may be modified in this manner.

While I have illustrated and described what I now contemplate to be the best modes of carrying out my invention, the constructions are, of course, subject to modification without departing from the spirit and scope of the invention. It is, therefore, not desired to restrict the invention to the particular forms of construction illustrated and described, but to cover all modifications that may fall within the scope of the appended claims.

Having thus described the invention, what I claim and desire to be secured by Letters Patent is:

1. A wall window construction comprising a rectangular main frame mounted in said wall, two side sashes each having an outline of a triangle with a vertical base, two slanting sides and an apex, the apex of said triangle projecting outwardly beyond the plane of said wall, said side sashes lying in two parallel vertical planes perpendicular to the plane of said wall, upper and lower sashes closing off the space outlined by said main frame and the four slanting sides of said two side sashes, two pairs of pivots mounted respectively on the upper and lower slanting sides of said side sashes, and a U-shaped channel rotatably supported by each pivot, said lower and upper sashes being slidably mounted in the respective U-shaped channels, whereby said upper and lower sashes are rotatable around the two pivots and slidable in and out along said U-shaped channels upon the rotation of said sashes into open positions.

2. A wall window as defined in claim 1, in which each of said upper and lower sashes includes a plurality of overlapping glass louvres.
